UNITED STATES PATENT OFFICE.

SAMUEL S. HALL AND JOSEPH WALMSLEY, OF BURY, NEAR MANCHESTER, ENGLAND.

WARPING AND BEAMING MACHINE.

SPECIFICATION forming part of Letters Patent No. 284,416, dated September 4, 1883.

Application filed March 31, 1882. (No model) Patented in England February 14, 1880, No. 661.

To all whom it may concern:

Be it known that we, SAMUEL STANDRING HALL and JOSEPH WALMSLEY, of Bury, near Manchester, England, have invented a new and useful Improvement in Warping and Beaming Machines, of which the following is a full, clear, and exact description, reference being had to the annexed drawings, forming part of this specification.

10 This invention relates to sectional warping and beaming machines; and the invention consists of certain improvements pertaining to different parts of the machine, as herein-after described and claimed.

15 In the drawings, Figure 1 is a side elevation, and Fig. 2 is a plan view, of a warping and beaming machine embodying our improvements. Fig. 1^a is an elevation, and Fig. 2^a is a plan view, of the starting-on motion. 20 Fig. 3 is an elevation of the measuring apparatus and a part of the stop-motion, and Fig. 3^a is a detail view of the stop-motion. Figs. 4, 5, 6, and 7 are detail views of other parts of the machine, and Fig. 8 shows a modified 25 form of gearing.

On the drum-shaft *a* are mounted two bevel-pinions, *a'* *a''*, either of which is adapted to engage with a bevel-pinion, *b'*, on one end of the shaft *b*. On the opposite end of the 30 shaft *b* is a friction-roller, *c*, which is adapted to drive the section-shaft *d'* by means of the friction-plate *d*, forming one of the flanges against which the section of warp is wound. The roller *c* is loosely mounted on the shaft *b*, and is connected to a screw, *c'*, by means of 35 a clutch-fork placed in engagement with a collar on the roller, and having a threaded perforation to receive the screw, so that as the screw is rotated in its bearings the clutch-fork will move thereon and cause the roller to 40 be adjusted automatically along the shaft *b* and along the radius of the friction-plate or flange *d*. In order that the adjustment of the roller along the radius of the plate *d* shall correspond to the speed of the section-shaft *d'*, 45 the screw *c'* is provided with a ratchet-wheel, *c''*, which is rotated to turn the screw and adjust the said roller by means of a pawl on one end of the elbow-lever *c''*, (see Fig. 7,) and an 50 eccentric, *d''*, on the section-shaft *d'*, in contact with which eccentric the free end of the lever *c''* is placed. At each revolution of the cam the lever is rocked and the pawl moves

the ratchet. The action of the pawl is adapted to be regulated by a slot in the eccentric 55 *d''*, whereby the latter can be adjusted nearer to or farther from the center of the shaft *d'* to vary the sweep of the lever.

In practice the roller *c* is to be so adjusted that it will be moved along the radius of the 60 plate *d*, from near the center to the circumference thereof, during each operation of winding a section of warp on the shaft *d'*. The object of so adjusting the friction-roller is to 65 vary the speed of the section-reel, so that the warp shall be wound thereon at a uniform rate of speed from beginning to end. As the section increases in diameter by the successive 70 courses of warp wound in its formation, the warp, if the movement of section-reel were uniform, would necessarily be wound at an increasing rate of speed, which would tend to disturb the uniformity of tension on the warp, and thus cause the sections, when completed, to be unequal in size and in length of warp. 75 It is of great importance, however, when the sections come to be wound on the loom-beam, that such inequalities should not exist, and therefore we give a uniformly-decreasing 80 rate of speed to the section-reel as the diameter of the section increases by causing the driving friction-roller to be moved gradually nearer the circumference of the friction-plate *d*, which has the effect of throwing the said friction-gears into constantly-increasing 85 disproportion as regards the diameters of their acting frictional surface, and thus causing a corresponding disproportion of speed. For instance, if we begin the winding of a section-shaft moving at the rate of one hundred revolutions a minute, we may gradually diminish 90 this rate of speed so that the shaft shall move at the rate of only sixty revolutions a minute at the completion of the section, and thus the warp may be drawn off from the beaming-frame under a uniform tension, notwithstanding 95 the increasing diameter of the section into which it is wound.

For certain patterns it is important that the warp of some of the sections shall be wound 100 in a reverse direction from that of others. To adapt the machine to be reversed at will for this purpose the pinions *a'* *a''* on the drum-shaft *a* are connected together by means of a rack-bar, *f'*, and clutch-forks *f''*, taking into 105 grooves in the bosses of the pinions, and a

pinion, f' ; secured to a shaft, f , is placed in engagement with the rack-bar, and is adapted to be rotated by a handle, f^4 , on the shaft f to shift the rack-bar and cause the pinions $a' a^2$ to move along the shaft a . Either of the pinions $a' a^2$ may thus be thrown into engagement with the pinion b' on the shaft carrying the driving friction-roller, and the motion of said roller may be reversed accordingly to change 10 the direction of the winding of the warp on the section-shaft.

To determine whether a given number of yards of warp is being wound into each section, we provide a measuring apparatus, (shown in 15 Figs. 1, 2, and 3,) consisting of the half-yard-measuring roller A , over which the warp passes as it is drawn off from the beaming-frame, and the dial B , adapted to register the revolutions of said roller. The shaft of the roller A is 20 provided with a worm, A' , which is geared with the change-wheel F by the intermediate gear-wheels, $F^1 F^2$, and the shaft of the change-wheel is provided with a worm, F^3 , gearing with a pinion, F^4 , on the shaft of the dial. A given number of revolutions of the roller A 25 will thus produce a corresponding number of revolutions of the dial-plate, and the number of half-yards of warp passed over the roller will be recorded on a graduated scale on the dial by a stationary pointer, F^5 , as shown in Fig. 2. On the shaft of the change-wheel F is secured a cam, E , (see Figs. 3, 3',) and a spring-hammer, D , having a projection thereon bearing against the cam, is adapted to be 30 forced back by the revolution of the cam until the projection on the hammer slips off the eccentric lip of the cam and causes the hammer to strike the bell C . An audible signal is thus given at each revolution of the cam, which 35 represents a given number of revolutions of the measuring-roller, and consequently a given number of yards of warp which should have passed over said roller to the section-shaft if the tension on the warp is properly adjusted. 40 To determine whether said given number of yards have actually been wound into the section, the section-shaft is provided with a worm, p , with which engages a wheel, p' , adapted to record the revolutions of said shaft. The wheel 45 p' is to be provided with holes, into which a number of pegs may be inserted by the operator to tally the revolutions of said wheel. A given number of revolutions of this wheel will 50 represent a given number of revolutions of the section-shaft. A given number of revolutions of the section-shaft represent a given number of yards wound into the section, supposing the tension to be properly adjusted, and if the operator observes that the given 55 number of yards announced by the bell-signal of the measuring-roller have been recorded by the wheel p' , he will understand that the tension on the warp is properly adjusted, and that the size of the section properly corresponds with the number of yards wound therein. Any discrepancy between the record of 60 the bell and that of the wheel p' will indicate

that the tension on the warp is either too slack or too taut, and that the section is not increasing in size in such proportion that a required 70 number of yards shall be contained in a completed section of a required size. In such case the tension on the warp is to be adjusted to produce the desired effect.

In order to be able to stop the machine instantly when a desired number of yards of warp have been wound into a section, and to start it again at a high rate of speed without loss of time, we provide a starting-on motion and a stop-motion, which we will now proceed 75 to describe.

Referring to Figs. 1^a and 2^a, H indicates a band pulley or drum, which is loosely mounted on the shaft a , and I is a friction-plate rigidly secured to the end of said shaft, which plate is 80 adapted to receive motion from the pulley when the latter is held in contact therewith. As a means of adjusting the pulley into contact with the plate, a clutch-collar, A' , is loosely mounted on the shaft a on the opposite side 85 of the pulley from the plate, and to this collar is rigidly attached a lever, B' , to one end of which is pivoted a vertical rod, C' , having a lip, D' , adapted to engage with a supporting-bracket, E' , and to be held yieldingly in engagement 90 therewith by a spring, F' . For moving the rod C' upward into such engagement with the bracket E' , a jointed foot-lever, G' , is adapted to depress the end of lever B' opposite from that to which the rod C' is connected, as shown in dotted lines, so as to throw said lever from a horizontal to an inclined position. When 95 thus depressed, the lever causes the clutch-collar A' to turn upon the shaft a with its bevel moving against the corresponding bevel of a stationary clutch-collar, A^2 , which gives a longitudinal movement to the collar A' , causing 100 it to slide against the pulley H and to force the latter into contact with the plate I . In this manner motion may be instantly communicated to the plate I , and through it to the shaft a , which runs the machine, and the motion will 105 continue to be communicated so long as the rod C' is allowed to remain in engagement with the bracket E' . The upper end of the 110 rod C' is provided with a cord, k , passing around pulleys C^2 and connected at its other end to the weighted rod i , which is adapted, under conditions yet to be explained, to fall and draw the rod C' to one side, so that the 115 lip D' on the said rod may slip off the bracket E' and allow the rod to drop through the bracket, and the lever B' thereby to regain its normal position. To force the rod C' and the lever B' to move as described, the lever B' is 120 connected to an oscillatory frame, J , which is provided with a weight, K , adapted to overbalance the lever B' when the latter is not locked by the engagement of the rod C' with the bracket E' . When the lever B' is thus 125 lifted to the position shown in full lines, the collar A' is rotated in such manner that the bevel of its clutch is moved from the corresponding bevel of the stationary clutch, and 130

the pressure on the drum is thus released, allowing the latter to move out of contact with the friction-plate, whereupon the machine may be stopped.

5 The weighted rod, which is adapted to operate the rod C' by means of the cord k , is adapted to be supported in a bracket, i^2 , by means of a projection, i' . Inserted in a circular plate, j^3 , which is mounted on the change-wheel stud j , is an eccentrically-located pin, j' , which is adapted at each revolution of the said plate and change-wheel to strike the rod i and cause the projection i' to slip from the supporting-bracket i^2 and allow the rod to drop. 10 In the circular plate j^3 is a slot, j^4 , (see Fig. 3^a), and in the slot is a screw, j^5 , fixed in the boss of the bell-cam, by which means the plate and pin are to be adjusted to allow the rod to be raised into position for acting again. A weight, i^3 , 15 is attached to the lower end of the rod i to secure the proper operation of the rod C' when the rod i is caused to fall. In this manner, at each revolution of the change-wheel, which represents a given number of yards wound into 20 the section, the machine is made to stop automatically, and thus each section may be made to contain exactly a desired number of yards of warp. We weight the section by means of the compound levers m and n , to the latter of 25 which is secured an iron strap, n' , lined with leather, which passes over a ratchet-roller on the pressure-shaft r , and is pulled down to bind the ratchet by means of the weight on lever n . The lever m , which is weighted, and the 30 arm carrying the roller s are rigidly attached to the same shaft, r , with the ratchet, and are so arranged with respect to each other that the said weighted lever m will cause the roller to bear up against the section, and the roller will 35 be kept from vibrating by the binding effect of the leather lining of the strap n' upon the ratchet-roller. The weighted lever n , with its strap n' , thus serves as a brake for binding the ratchet and holding it against the action of 40 the weight of lever m so that the rotation of the section in contact with the pressure-roller s cannot cause the roller to vibrate, but will move it down gradually against the effect of the weight on lever m as the diameter of the 45 section increases. By this mechanism, of which a plan view is given in Fig. 4, the pressure-roller is made to bear equally upon the different layers or courses of the section, to the end that all the sections, when completed, shall 50 be of an equal diameter.

The wraith o , which is shown enlarged in Fig. 5, is made in two parts, o^2 o^3 , hinged together end to end, and provided with suitable connections, o^4 , with a right and left hand screw 55 cut on the spindle o' , whereby the two parts may be expanded or contracted by rotating the spindle.

In Fig. 8 we show a modified form of gearing for driving the section-flange. The flange 60 is provided on one side with concentric toothed or pegged rings d^4 , one arranged within another, and the frictional driving-shaft b is pro-

vided with a pinion, d^5 , adapted to gear with any one of the rings d^4 . When this gearing is used instead of the frictional gears c d , the machine must be stopped to move the pinion from one ring of the flange to the next. 70

What we claim is—

1. The combination, with the section-shaft, the measuring-roller, and means for registering 75 the revolutions of the latter, of the drum-shaft and means for gearing it with the section-shaft, the loose drum mounted on the shaft, the friction-plate secured to the drum-shaft, the clutch-collar, the lever secured thereto, and means 80 for causing the collar to slide against the drum and force it against the plate, a device for holding the lever in a given position, the weighted rod connected by a cord to the said device, and means for supporting the rod, and a tripping 85 device for the rod, which is adapted to be operated by the measuring-roller, substantially as shown and described.

2. The combination, with the section-shaft, the measuring-roller, and means for registering 90 the revolutions of the latter, of the driving-shaft and means for gearing the same with the section-shaft, the loose drum and means for connecting it with the driving-shaft, a device for setting the drum in gear with the shaft, and 95 means for ungearing the drum from the shaft automatically, substantially as shown and described.

3. The combination, with the section-shaft, of the drum-shaft, the two sliding pinions on 100 the drum-shaft, the rack-bar connecting the said pinions, the shaft and pinion for operating the rack-bar to adjust the sliding pinions, and the shaft and gearing for communicating motion to the section-shaft, substantially as 105 shown and described.

4. The combination, with the section-shaft, of the friction-roller placed in contact with a flange on the shaft, and means for driving the roller, a threaded shaft, an arm screwing on 110 said shaft and connected to the said roller, a ratchet-wheel on said shaft, a pawl-lever for operating the ratchet, and a cam on the section-shaft for operating the lever, substantially as shown and described, whereby the 115 friction-roller shall be caused to move gradually from a point near the center of the flange on the section-shaft toward its edge, for the purpose specified.

5. The combination, with the section-shaft 120 and means for driving the same, of the pressure-roller adapted to bear against the warp on the section-shaft, the weighted levers m n , the ratchet, and strap n' , all arranged and adapted to operate substantially as shown and 125 described.
